MODULAR WALL PANEL FOR HOSPITAL IN-PATIENT CARE

William R. Hall, 10573 Lauriston Ave.,
Los Angeles, Calif. 90064

Filed Jan. 17, 1974, Ser. No. 434,011

Term of patent 3½ years

Int. Cl. D24—01

U.S. Cl. D83—1 F

FIG. 1 is a perspective view of a modular wall panel for hospital in-patient care embodying my new design;

FIG. 2 is a side elevational view from the right side of FIG. 1;

FIG. 3 is a side elevation as viewed from the left side of FIG. 1;

FIG. 4 is a rear elevational view; and

FIG. 5 is a bottom plan view.

I claim:

The ornamental design for a modular wall panel for hospital in-patient care, as shown and described.
